WINDOW STOP

Frederick J. Uecker, Philadelphia, Pa., assignor
to Edward G. Budd Manufacturing Company,
Philadelphia, Pa., a corporation of Pennsylvania

Application April 22, 1932, Serial No. 606,829

5 Claims. (Cl. 296—44)

My invention relates to vehicle structures and particularly to stops for the glass window elements of automobiles.

Objects of my invention include primarily the provision of a stop of the above indicated character, or a device similar thereto for analogous purposes that shall facilitate the manufacture and assembly of the parts constituting the same and associated therewith, that shall be effectively shaped and braced, that shall conserve space, weight and material, that shall be effective in its operation and that shall have other advantages incident to the utilization of the improvement.

15 In the provision of a window-glass stop at an intermediate position on the inner sheet-metal panel of an automobile wall or door panel it has heretofore been usual to punch a tongue or lug and bend it out of the plane of the sheet.

20 It has been usual to merely bend out a flat sheet metal tongue that is either unsupported or reinforced by connection to the outer wall or door panel and, in either case, the resultant structure is comparatively weak or required comparatively difficult and expensive reinforcing operations.

25 In practicing my invention, I provide a stop that is so punched from a metal sheet and that is of such configuration and relation to the remaining portions of the sheet as to constitute a rigid, permanent and effective structure having several features of improvement over similar devices heretofore employed.

Fig. 1, of the accompanying drawing, is a perspective view of the inner panel of the door of an automobile, as viewed from the exterior of the car, the outer panel being removed.

35 Fig. 2 is an enlarged detailed view, in elevation, of the device shown in Fig. 1, as viewed in the 40 direction of the arrow II, and

45 Fig. 3 is an enlarged view, taken substantially along the line III—III of Fig. 1.

The inner panel of the door comprises a single piece of relatively thin sheet metal that is die stamped, pressed and cut from an initially flat sheet of metal.

50 It comprises a perimetral flange 2 for receiving a crimped edge flange 3 of the outer panel 5, a window opening 4, jamb rail portions 6 and a window-glass stop structure 8 of my invention. The outer panel 5 has a usual opening similar to the opening 4 and in register therewith to form the window opening of the door.

55 The stop structure 8 has a portion in the form of a tongue that is stamped, or otherwise sev-

ered about three sides from the panel to have a base portion 10 remaining integral with the panel, a relatively narrow preferably parallel-sided section 12 adjacent to the base 10 and a preferably gradually widening portion 14 extending from the narrow portion 12 to an outer end portion 16 thereof.

60 A slot 18 in the panel is consequently, of a shape, similar to the tongue, having a narrow portion 20 and a widened portion 22.

65 Pressed portions or indentures 24 are provided at opposite sides of the slot in the panel adjacent to the intersection of the wide and narrow slot sections to constitute anchorages or shoulders for the tongue end 16 which is wider than the 70 slot at this location.

75 In shaping the tongue, after it has been stamped or cut from the panel, it is bent transversely to the plane of the panel about an axis, preferably at or near the base end 10 of the tongue, to render the narrow portion 12 of the tongue the stop portion, against which a window glass, not shown, is adapted to rest in its inner or lowermost position between the door panels.

80 Adjacent to the outer end 11 of the stop portion 12, the tongue is reversely bent to render the widened portion 14 substantially a brace between the stop 12 and the panel. The brace 14 not only slopes at an angle to the panel, but also tapers along its edges from adjacent 85 to the outer tongue end 16 to the outer end 11 of the stop, thus providing wide bases and a substantially pyramidal structure of high resistance against both vertical and horizontal forces.

85 The end portion 16 is preferably bent to have 90 a short section thereof in substantially parallel side surface engagement with the panel over a substantial area thereof at each side of the slot 18. This structure provides adequate area for, and facilitates the application of, weld spots 26 95 joining the portion 16 of the panel. Also, by having the portion 16 rest on the shoulders 24, the weld spots 26 are relieved of the main supporting and impact forces of the glass on the stop 12 normal to the plane of the shoulders, 100 or in a direction substantially parallel to the door panel.

105 The invention provides a substantially triangular stop structure, in which the sides are rigidly braced, in contradistinction to an unsupported lug or tongue that is merely bent at right angles to the panel, and in a more advantageous manner than a shelf or stop bridged between the outer and inner panels 5 and 6, respectively.

110 While I have shown and described a particular

form of my invention, changes may be effected therein without departing from the spirit and scope thereof as set forth in the appended claims.

I claim as my invention:

- 5 1. A vehicle window-glass stop comprising a sheet-metal panel and an element struck out of the panel in the form of a tongue, bent to form with the panel as one side, a substantially triangular bracket having a stop portion projecting from the panel and a diagonal brace portion between the stop portion and the panel, the panel having a struck-up portion constituting a shoulder support for the inner end of the diagonal-brace portion.
- 10 2. A vehicle window-glass stop comprising a sheet-metal panel and an element struck out of the panel in the form of a tongue, bent to form with the panel as one side, a substantially triangular bracket having a stop portion projecting from the panel and a diagonal brace portion between the stop portion and the panel, the panel having a struck-up portion constituting a shoulder support for the inner end of the diagonal-brace portion which is welded to the panel.
- 15 3. A vehicle window-glass stop comprising a sheet-metal panel and an element struck out of the panel in the form of a tongue bent about axes parallel to the panel, to form with the panel as one side, a triangular bracket having a stop portion projecting from the panel and a diagonal brace portion between the stop portion and the

panel, the brace portion having a laterally projecting portion resting against the panel beside the slot formed in the panel by striking out the tongue.

- 80 4. A vehicle window-glass stop comprising a sheet-metal panel and an element struck out of the panel in the form of a tongue bent about axes parallel to the panel, to form with the panel as one side, a triangular bracket having a stop portion projecting from the panel and a diagonal brace portion between the stop portion and the panel, the brace portion having a laterally projecting portion parallel, and spot welded, to the panel beside the slot formed in the panel by striking out the tongue.

- 85 5. A vehicle window-glass stop comprising a sheet-metal panel and an element struck out of the panel in the form of a tongue bent about axes parallel to the panel, to form with the panel as one side, a triangular bracket having a stop portion projecting from the panel and a diagonal brace portion between the stop portion and the panel, the brace portion having a laterally projecting portion parallel, and spot welded, to the panel at opposite sides of the slot formed in the panel by striking out the tongue and edges sloping between said laterally projecting portion and the outer end of the stop portion.
